CLAIM

The ornamental design for a communication device, as shown and described.

DESCRIPTION

FIG. 1 is an isometric view of an ornamental design for a communication device showing our new design;

FIG. 2 is a rear orthographic view thereof;

FIG. 3 is a front orthographic view thereof;

FIG. 4 is a right side orthographic view thereof;

FIG. 5 is a left side orthographic view thereof;

FIG. 6 is a top orthographic view thereof; and,

FIG. 7 is a bottom orthographic view thereof.

The broken lines shown in FIGS. 1-7 that are immediately adjacent to the shaded areas represent the bounds of the claimed design, while all other broken lines are directed to environment and are for illustrative purposes only; the broken lines form no part of the claimed design.
